SHOE BOTTOM IRONING DEVICES

Arthur R. Hubbard, Beverly, Mass., assignor to United Shoe Machinery Corporation, Boston, Mass., a corporation of New Jersey

Application July 23, 1957, Serial No. 673,653

24 Claims. (Cl. 12—53.5)

This invention relates to shoe bottom ironing devices, and particularly to an improved device for ironing the shank and heel seat portions of shoes.

In United States Letters Patent No. 2,654,903, granted October 13, 1953, on an application filed in the name of Ferman N. Lee, there is disclosed a device for performing the above-mentioned heel seat and shank ironing operation, including a heel ironing block having a generally flat operating surface and two sets of articulated shank ironing members, hinged to the heel ironing block adjacent to one edge of its operating surface and shaped to present a curved operating surface for ironing the lasted margin of the upper at the opposite sides of the shank portion of a shoe. In this prior device, the heel ironing block, together with the shank ironing members hinged thereto, are supported for pivotal movement as a unit in order that the generally flat operating surface of the heel ironing block and the curved operating surfaces of the shank ironing members may be caused to conform generally to the shape of the heel seat and shank portions of the shoe. Moreover, these shank ironing members are connected to each other and to the heel ironing block by means of a series of equalizing levers which permit relative movement between the shank ironing members and the heel ironing block so that the ironing pressure is equally distributed over the entire heel seat and along the shank portion of the shoe when the shoe is forced against the device as, for example, by means of a fluid pressure operated abutment member. While this prior arrangement operates in a generally satisfactory manner and as explained in the mentioned patent, it has been found in practice that there is some tendency, especially if the shoe is improperly located in a lengthwise direction relatively to the device, for the pressure applied to the bottom of the shoe to "break" the last. Moreover, experience seems to indicate that it would be advantageous to be able to apply considerably greater ironing pressure to the generally flat heel seat portion of the shoe by the heel ironing block than is required, or desirable, to be applied to the shank portion thereof by the shank ironing members.

A principal object of this invention is, accordingly, to provide a novel and improved device for ironing the shank and heel seat portions of the bottoms of shoes whereby the above objection may be avoided and the mentioned advantage obtained. With this purpose in view and in accordance with a feature of the invention, in the herein illustrated device, which comprises a heel ironing block having a generally flat operating surface with shank ironing members hinged thereto and an abutment member mounted for movement to press the heel seat portion of a shoe against the heel ironing block, separate power means are provided for moving the abutment and for swinging the shank ironing members relatively to the block to force the shank ironing members against the shank portion of the shoe. Preferably, and in accordance with other features of the invention, separate fluid pressure means are provided for moving the abutment member and for swinging the shank ironing

2

members relatively to the heel ironing block, and the fluid pressure means for swinging the shank ironing members is operable in response to the operation of the fluid pressure means for moving the abutment member. Also, separate means are provided for varying the forces exerted by each of these fluid pressure means. More particularly, the herein illustrated device, which includes a rigidly mounted heel ironing block having two sets of shank ironing members hinged thereto for bodily movement about angularly disposed axes, each of the sets of shank ironing members including a pair of articulated blocks, an abutment member for engaging the heel cone of the last of a shoe and mounted for movement to press the heel seat of the shoe against the block, fluid pressure means for effecting movement of the abutment member, an equalizing lever associated with each of the sets of shank ironing members, together with means for varying the force exerted by the mentioned fluid pressure means, is provided with a separate fluid pressure means operable in response to the operation of the first-mentioned fluid pressure means for actuating the mentioned equalizing levers, together with means for varying the forces exerted by each of said fluid pressure means independently of the other.

The above and other objects and features of the invention will appear in the following detailed description of the preferred embodiment thereof illustrated in the accompanying drawings, and will be pointed out in the claims.

In the drawings,

Fig. 1 is a view in side elevation of a device for ironing the shank and heel seat portions of the bottoms of shoes and embodying the features of this invention;

Fig. 2 is a view in front elevation and at an enlarged scale of a part of the device shown in Fig. 1;

Fig. 3 is a view in rear elevation also at an enlarged scale of another part of the device, and

Fig. 4 is a schematic drawing of the fluid pressure system for operating the device.

Referring to these drawings, and particularly to Fig. 1, it will be observed that the device therein illustrated is generally similar to that disclosed in the patent to Lee, mentioned above, and has a heel ironing block 10, provided with a generally flat operating surface 12, to which there are hinged two sets of shank ironing members, each comprising a pair of hinged-together or articulated blocks 14, 16 having curved operating surfaces 18, 20 which form continuations of the flat operating surface 12 of the block 10. Preferably, and as herein illustrated, the operating surfaces 12, 18, 18, 20, 20 are covered by a thin sheet of metal 22 shaped as shown in Figs. 1 and 2 of the drawings. The block 10 is secured, by means of screws 24, 24, to the lower edges of two web-like portions 30, 30 formed integrally with a frame construction, indicated generally by the reference character 32 and having a top part 34 and a base part 36, Fig. 1.

Supported on the base part 36 of the frame construction is a main cylinder 40 provided with a bore 42 in which there is fitted a large piston 44. This piston has a central bore 46, closed at its lower end by means of a cover plate 48, and fitted within this bore is a small piston 50 having a rod 51 which extends upwardly through a bore 52 formed in a header block 54 secured to the upper end of the cylinder 40, and a downwardly extending stem 56. Pinned to the upper end of the rod 51 is a member 60 on which there is adjustably mounted a supporting block 62 for an abutment plate 64 which is mounted thereon for limited universal tilting or rocking movement by means of an annulus 66 of rubber or similar resilient material. Rotation of the rod 51 is prevented and upward movement of the rod 51 is limited, when there is no shoe on the abutment plate 64, by a pin 63 which enters

a groove 65 in the rod 51. The plate 64 is also provided with a projection having a spherical surface 68, adapted to be brought into frictional locking engagement with a conical surface 70 on the block 62 when the annulus 66 is compressed, and is held in assembled position on the block by means of a coil spring 72. As will presently appear, the abutment plate 64 is elevated by means of the pistons 44 and 50 into engagement with the cone portion of the last L of a shoe S to press the heel seat of the shoe firmly against the operating surface 12 of the heel ironing block 10 or, more accurately, against the thin metal plate 22, when it is provided. Thereafter, and while the heel seat is being ironed in this manner, the shank ironing members are swung in a clockwise direction, Fig. 1, in order to apply ironing pressure, through the action of the plate 22, when it is provided, to the curved shank portion of the bottom of the shoe.

Referring to Fig. 1, the blocks 14, 16 of each shank ironing member are held in the positions in which they are shown by means of a coil spring 80, see also Fig. 2, with surfaces 82, 84 formed on the upper ends of these blocks, respectively, bearing against rollers 86, 88 carried by an equalizing lever 90. Each of these equalizing levers is pivotally mounted by means of a pin 91 on the forward end of a lever 92 which extends forwardly and rearwardly beyond a pin 94 by means of which it is pivotally supported on one of the web portions 30 of the frame 32. Mounted in the rearward end of each of the levers 92 is an abutment pin 96 which is in engagement with an equalizing lever 100, Fig. 3. This equalizing lever is mounted on a pin 102 which is carried by upstanding ears 104, 104 formed on the upper end of the piston rod 106 of a piston 108. This piston rod extends through a bore 110 in an end member 112 associated with a cylinder 114 provided with a bore 116 in which the mentioned piston 108 is fitted. The cylinder 114 is supported on two web portions 120, 120 of the frame construction 32 by means of the end member 112 which is secured thereto by screws 122, 122, Fig. 3. A spring-pressed plunger 124 is provided for yieldingly holding the equalizing lever 100 in the position in which it is shown, while an enlarged end 126 on the pin 102 is fitted within a slot 128 formed in an upstanding ear 130 on the end member 112 to prevent rotation of piston 108 and the lever 100 carried thereby.

Referring to Figs. 1 and 4, a conduit 140 is connected to the lower end of the cylinder bore 42 through a port 142 in the base 36; a conduit 144 is connected to the bore 46 through an annular groove 146 on the piston 44 and a radial port 147 in that piston; a conduit 148 is connected to the lower end of the cylinder bore 116 below the piston 108; while the space in the bore 42 above the piston 44 and the space in the cylinder bore 116 above the piston 108 are connected to a conduit 150. As is indicated in Fig. 4, an accumulator A, which is kept charged with operating fluid, such as oil under pressure from a source not shown, is connected through lines *a* and *b* to a solenoid-operated valve V-1 and a fluid pressure operated valve V-2. A spring 160 normally holds the plunger of the valve V-2 in a position such that the conduit 150 is connected to the accumulator through a line *c* so that operating fluid under pressure holds the pistons 44 and 108 in the retracted positions in which they are shown and also holds the plunger 162 of a fluid operated check valve V-3 in the operating position in which it is shown, thereby connecting the conduit 144 with a line *d* which leads from the valve V-2 through the valve V-3 to a sequence valve V-4, this line now being connected to exhaust through the valve V-2. The sequence valve V-4 is connected to a manually adjustable pressure reducing valve V-5 which in turn is connected to the conduit 140, and to a line *e* one end of which leads back to the valve V-3, as shown, while the other end is connected to a second sequence valve V-6. The sequence valve V-6 is connected by means of a line *f* to a second pressure reducing

valve V-7 which, in turn, is connected to the conduit 148. It will be understood that the several different valves referred to above, and illustrated schematically in Fig. 4 of the drawings, are of well-known construction so that no detailed description of these valves is thought to be necessary.

With the arrangement so far described and schematically illustrated in Fig. 4, when a solenoid *S* associated with the valve V-1 is energized in a manner about to be explained, operating fluid under pressure is permitted to flow through the line *a* thereby shifting the plunger of the valve V-2 to a position in which line *c* is connected to exhaust and line *d* is connected to line *b* and hence to the accumulator A. Operating fluid under pressure now flows through the conduit 144 and elevates the piston 50 to press the heel seat of the shoe S, presented to the device by an operator as shown in Fig. 1, against the heel ironing block 10 with a relatively light force, the abutment plate 64 now tilting or rocking, as required, to provide even pressure on the heel seat of the shoe. As the pressure builds up in the conduit 144 and also in the line *d* to the intensity for which sequence valve V-4 is set, approximately 75 p. s. i., this valve opens and admits operating fluid under pressure to the line *e*. Pressure of the operating fluid in the line *e* causes the plunger 162 of the valve V-3 to move to closed position, thereby trapping operating fluid in the cylinder bore 46 beneath the piston 50 while still permitting flow of operating fluid through the line *d*. Operating fluid from the sequence valve V-4 flows through the pressure reducing valve V-5, which can be set to the desired pressure, through the conduit 40 and thence to the cylinder 42 beneath the piston 44. This piston is now elevated to cause the heel seat of the shoe to be pressed very firmly against the heel ironing block 10 with the greater force desired and as controlled by the setting of the valve V-5.

When the pressure of the operating fluid in the line *e* builds up to the intensity for which the sequence valve V-6 is set, approximately 220 p. s. i., this valve opens and operating fluid flows through line *f* and the second pressure reducing valve V-7 to the conduit 148 and thence to the cylinder bore 116 below the piston 108. As this piston is elevated by the pressure of the operating fluid, the shank pressing members comprising blocks 14 and 16 will be swung in a clockwise direction, Fig. 1, to cause their operating surfaces, acting through the thin metal plate 22, to exert ironing pressure on the shank portion of the shoe, the force exerted by these shank pressing members being determined, of course, by the setting of the valve V-7 and independently of the pressure being exerted by the heel ironing block on the heel seat of the shoe. Pins 81, see Fig. 1, associated with the springs 80, serve as stops to limit swinging movements of the levers 92, when no shoe is on the plate 64. As will presently appear, the solenoid *S* is deenergized after a predetermined time interval and when this happens pistons 44, 50 and 108 are returned to their original positions, as shown in Figs. 1 and 4 of the drawings, in a manner which will be obvious, thus releasing the shoe.

Referring to Figs. 1 and 2, there is mounted for vertical sliding movement in the top part 34 of the machine frame 32, a plunger 180 to the upper end of which there is secured a head piece 182. At its lower end this plunger is shaped to provide a sensing finger 184 which projects downwardly between the two sets of shank ironing members and through an opening 186 in the thin metal plate 22, Fig. 2. A spring 188, interposed between a collar 190 on the plunger 180 and the top part 34 of the frame, yieldingly urges the plunger downward to the extent determined by the engagement of the head piece 182 with the frame. Mounted on the top part of the frame within a housing 194 is a pneumatic timing device, indicated generally by the reference character T, and of a well-known commercial type, which is connected to the solenoid *S* through an electrical lead indicated by the

line *l*. The timing device *T* is adapted, in response to the inward movement of a button *196*, to connect the lead *l* to another lead *m* from a source of electrical energy not shown for an adjustably predetermined time interval.

For operating the button *196* there is pivotally mounted on the head piece *182* an arm *200* which is yieldingly held, by means of a spring plunger *202*, in a position to engage a lip *204* formed on a lever *206* having an upper arm *208* adapted to engage the button and a lower arm *210* carrying a screw *212*, and pivotally mounted on a bracket *214* which supports the timing device. With this arrangement, when the plunger *180* is elevated in response to pressure of the bottom of a shoe presented to the machine on the sensing finger *184*, the button *196* will first be pushed inwardly thereby setting the timing device into operation, as a result of the rocking of the lever *208* in a counterclockwise direction. As this rocking movement is continued during further upward movement of the plunger *180*, the screw *212* will eventually strike the arm *200* and swing it in a clockwise direction out from beneath the lip *204*, thereby releasing the button *196* of the timing device. At the end of the interval for which the timing device is set, the ironing operation is terminated and the shoe is ejected from the device in a manner about to be described. When this occurs the plunger *180* is moved downwardly by the spring *188*, and lever *206* and arm *200* are returned to their original positions as shown in Figs. 1 and 4.

For assisting the operator in locating the heel end of a shoe laterally as it is presented to the machine, a V-shaped heel abutment *220* is provided, and this abutment is formed integrally with the upper ends of a pair of arms *222*. At their lower ends these arms are pivotally mounted on a header block *54* by means of a pin *224*, and a spring-pressed plunger *226* is arranged to swing the arm *222* in a clockwise direction and to the position indicated in Fig. 1 as determined by an adjustable stop screw *228*. Also mounted on the header block *54* is a suitable shoe receiver indicated generally by the reference character *230*. In presenting a shoe to the machine, the operator causes its heel end to engage and to push the heel abutment *220* to the left, Fig. 1, far enough to bring the heel seat of the shoe directly beneath the heel ironing block *10* and also to locate the cone of the last *L* directly over the abutment plate *64*. When the shoe is released at the conclusion of the ironing cycle, it is pushed to the right by the action of the plunger *226* and drops into the receiver *230*.

As will be apparent with the novel arrangement described above, by suitable adjustment of the two pressure reducing valves *V-5* and *V-7*, the forces exerted, respectively, by the abutment *64* to press the heel end of a shoe against the heel ironing block *10* and by piston *108* to swing the shank ironing members *18*, *20* relatively to the heel ironing block, so as to force these members against the shank portion of the shoe, may be independently varied by the operator as desired to suit different operating conditions. Accordingly, it is possible to obtain adequate ironing pressure for the relatively flat heel seat portion of the shoe and at the same time to limit the force exerted by the shank ironing members to an amount sufficient to assure proper ironing of the upper materials in the shank portion of the shoe without, however, having these members exert a sufficient force to "break" the last.

The heel ironing block *10* is heated by means of electrical heating units *240*, *240*, while the shank-ironing members *18*, *20* are provided with electrical heating units *242*, *244*. Preferably, these sets of heating units are adapted to be controlled independently of each other so that temperatures suitable for ironing the heel seat and shank portions of each shoe are assured. In addition, it may be noted that the timing device *T* assures an adequate period of ironing pressure without any danger of overheating or burning of the upper materials by the heated ironing members, while the heel centering abutment *220*

greatly facilitates the placing of shoes in the device and in this way tends to speed up the heel seat and shank ironing operation.

Having thus described the invention, what I claim as new and desire to secure by Letters Patent of the United States is:

1. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, power means for effecting such movement of said abutment member, and separate power means for swinging said shank ironing members relatively to the heel ironing block to force the shank ironing members against the shank portion of the shoe.
2. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, fluid pressure means for effecting such movement of said abutment member, and separate fluid pressure means for swinging said shank ironing members relatively to the heel ironing block to force the shank ironing members against the shank portion of the shoe.
3. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, power means for effecting such movement of said abutment member, and separate power means operable in response to the operation of said first mentioned power means for swinging said shank ironing members relatively to the heel ironing block to force said shank ironing members against the shank portion of the shoe.
4. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, fluid operated means for effecting such movement of said abutment member, and separate fluid operated means operable in response to the operation of said first mentioned fluid operated means for swinging said shank ironing members relatively to the heel ironing block to force the shank ironing members against the shank portion of the shoe.
5. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, power means for effecting such movement of said abutment member, means

for varying the force exerted by said power means, and separate power means for swinging said shank ironing members relatively to the heel ironing block to force the shank ironing members against the shank portion of the shoe, and means for varying the force exerted by said last-named power means independently of the force exerted by said first-named power means.

6. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, fluid pressure means for effecting such movement of said abutment member, means for varying the force exerted by said fluid pressure means, separate fluid pressure means for swinging said shank ironing members relatively to the heel ironing block to force the shank ironing members against the shank portion of the shoe, and means for varying the force exerted by said last-named fluid pressure means independently of the force exerted by said first-named fluid pressure means.

7. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, power means for effecting such movement of said abutment member, means for varying the force exerted by said power means, separate power means operable in response to the operation of said first-mentioned power means for swinging said shank ironing members relatively to the heel ironing block to force the shank ironing members against the shank portion of the shoe, and means for varying the force exerted by said last-named power means independently of the force exerted by said first-named power means.

means.

8. A device for use in ironing the shank and heel seat portions of the bottoms of shoes comprising a rigidly mounted heel ironing block having a generally flat operating surface and shank ironing members hinged to said heel ironing block adjacent to one edge of its operating surface, an abutment member for engaging the last of a shoe presented to the device and mounted for movement toward said heel ironing block to press the heel seat of the shoe against the block, fluid pressure means for effecting such movement of said abutment member, means for varying the force exerted by said fluid pressure means, separate fluid pressure means operable in response to the operation of said first-mentioned fluid pressure means for swinging said shank ironing members relatively to the heel ironing block to force the shank ironing members against the shank portion of the shoe, and means for varying the force exerted by said last-named fluid pressure means independently of the force exerted by said first-named fluid pressure means.

9. A device for use in ironing the shank and heel seat portions of the bottom of shoes comprising a rigidly mounted heel ironing block provided with a generally flat operating surface and two sets of shank ironing members hinged to said ironing block adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the

heel seat of the shoe against the block, power means for effecting such movement of said abutment member, an equalizing lever associated with each of said sets of shank ironing members, and separate power means for actuating said levers to swing the sets of shank ironing members relatively to the heel ironing block to force the shank ironing members against the shank portion of the shoe.

10. A device for use in ironing the shank and heel seat
10 portions of the bottom of shoes comprising a rigidly
mounted heel ironing block provided with a generally flat
operating surface and two sets of shank ironing members
hinged to said ironing block adjacent to one edge of its
15 operating surface, each of said sets of shank ironing
members including a pair of articulated blocks shaped to
provide a curved operating surface forming a continuation
of the operating surface of said heel ironing block,
an abutment member for engaging the heel cone of the
last of a shoe presented to the device and mounted for
20 movement toward said heel ironing block to press the
heel seat of the shoe against the block, fluid pressure
means for effecting such movement of said abutment
member, an equalizing lever associated with each of said
sets of shank ironing members, and separate fluid pressure
25 means for actuating said levers to swing the sets of shank
ironing members relatively to the heel ironing block to
force the shank ironing members against the shank por-
tion of the shoe.

11. A device for use in ironing the shank and heel
30 seat portions of the bottom of shoes comprising a rigidly mounted heel ironing block provided with a generally flat operating surface and two sets of shank ironing members hinged to said ironing block adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted
40 for movement toward said heel ironing block to press the heel seat of the shoe against the block, power means for effecting such movement of said abutment member, an equalizing lever associated with each of said sets of shank ironing members, and separate power means operable in response to the operation of said first-mentioned power means for actuating said levers to swing the sets of shank ironing members relatively to the heel ironing block to force the shank ironing members against the shank portion of the shoe.

50 12. A device for use in ironing the shank and heel seat portions of the bottom of shoes comprising a rigidly mounted heel ironing block provided with a generally flat operating surface and two sets of shank ironing members hinged to said ironing block adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the heel seat of the shoe against the block, fluid pressure means for effecting such movement of said abutment member, an equalizing member associated with each of said sets of shank ironing members, and separate fluid pressure means operable in response to the operation of said first-mentioned fluid pressure means for actuating said levers to swing the sets of shank ironing members relatively to the heel ironing block to force the shank ironing members against the shank portion of the shoe.

13. A device for use in ironing the shank and heel seat portions of the bottom of shoes comprising a rigidly mounted heel ironing block provided with a generally flat operating surface and two sets of shank ironing members hinged to said ironing block adjacent to one edge of its

means for actuating said levers to swing the sets of shank ironing members relatively to the heel ironing block to force the shank ironing members against the shank portion of the shoe.

20. A device for use in ironing the shank and heel seat portions of the bottoms of shoes comprising a rigidly mounted heel ironing block provided with a generally flat operating surface and two sets of shank ironing members hinged to said ironing block for pivotal movement about angularly disposed axes adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the heel seat of the shoe against the block, fluid pressure means for effecting such movement of said abutment member, an equalizing member associated with each of said sets of shank ironing members, and separate fluid pressure means operable in response to the operation of said first-mentioned fluid pressure means for actuating said levers to swing the sets of shank ironing members relatively to the heel ironing block to force the shank ironing members against the shank portion of the shoe.

21. A device for use in ironing the shank and heel seat portions of the bottoms of shoes comprising a rigidly mounted heel ironing block provided with a generally flat operating surface and two sets of shank ironing members hinged to said ironing block for pivotal movement about angularly disposed axes adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the heel seat of the shoe against the block, power means for effecting such movements of said abutment member, an equalizing lever associated with each of said sets of shank ironing members, means for varying the force exerted by said power means, separate power means for actuating said levers to swing the sets of shank ironing members relatively to the heel ironing block to force the shank ironing members against the shank portion of the shoe, and means for varying the force exerted by said last-named power means independently of the force exerted by said first-named power means.

22. A device for use in ironing the shank and heel seat portions of the bottoms of shoes comprising a rigidly mounted heel ironing block provided with a generally flat operating surface and two sets of shank ironing members hinged to said ironing block for pivotal movement about angularly disposed axes adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the heel seat of the shoe against the block, fluid pressure means for effecting

such movement of said abutment member, an equalizing lever associated with each of said sets of shank ironing members, means for varying the force exerted by said fluid pressure means, separate fluid pressure means for actuating said levers to swing the sets of shank ironing members relatively to the heel ironing block to force the shank ironing members against the shank portion of the shoe, and means for varying the force exerted by said last-named fluid pressure means independently of the force exerted by said first-named fluid pressure means.

23. A device for use in ironing the shank and heel seat portions of the bottoms of shoes comprising a rigidly mounted heel ironing block provided with a generally flat operating surface and two sets of shank ironing members hinged to said ironing block for pivotal movement about angularly disposed axes adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the heel seat of the shoe against the block, power means for effecting such movement of said abutment member, an equalizing lever associated with each of said sets of shank ironing members, means for varying the force exerted by said power means, separate power means operable in response to the operation of said first-mentioned power means for actuating said levers to swing the sets of shank ironing members relatively to the heel ironing block to force the shank ironing members against the shank portion of the shoe, and means for varying the force exerted by said last-named fluid pressure means independently of the force exerted by said first-named power means.

24. A device for use in ironing the shank and heel seat portions of the bottoms of shoes comprising a rigidly mounted heel ironing block provided with a generally flat operating surface and two sets of shank ironing members hinged to said ironing block for pivotal movement about angularly disposed axes adjacent to one edge of its operating surface, each of said sets of shank ironing members including a pair of articulated blocks shaped to provide a curved operating surface forming a continuation of the operating surface of said heel ironing block, an abutment member for engaging the heel cone of the last of a shoe presented to the device and mounted for movement toward said heel ironing block to press the heel seat of the shoe against the block, fluid pressure means for effecting such movement of said abutment member, an equalizing lever associated with each of said sets of shank ironing members, means for varying the force exerted by said fluid pressure means, separate fluid pressure means operable in response to the operation of said first-mentioned fluid pressure means for actuating said levers to swing the sets of shank ironing members relatively to the heel ironing block to force the shank ironing members against the shank portion of the shoe, and means for varying the force exerted by said last-named fluid pressure means independently of the force exerted by said first-named fluid pressure means.
